UNITED STATES PATENT OFFICE

171,223

ADVERTISING SIGN

Lewis E. Peters, Beverly Shores, Ind., assignor to
Raymond M. Price & Associates, Inc., Chester-
ton, Ind., a corporation of Indiana

Application April 15, 1953, Serial No. 24,509

Term of patent 3½ years

(Cl. D1—12)

To all whom it may concern:

Be it known that I, Lewis E. Peters, a citizen of the United States of America, residing at Beverly Shores, in the county of Porter and State of Indiana, have invented a new, original, and ornamental Design for an Advertising Sign, of which the following is a specification, reference being had to the accompanying drawing, forming a part thereof.

In the drawing:

Figure 1 is a front elevational view of an advertising sign showing my new design;

Figure 2 is a top plan view of the sign of Figure 1;

Figure 3 is a vertical sectional view of the sign of Figure 1, taken substantially along the plane of the line 3—3 thereof.

The dominant features of my design reside in the portions shown in full lines.

I claim:

The ornamental design for an advertising sign, as shown and described.

LEWIS E. PETERS.
